David S. Kennedy

BY

Roger Kennedy & Son, ATTORNEYS

UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

TYPOGRAPHICAL MACHINE.

Application filed August 25, 1921. Serial No. 495,306.

To all whom it may concern:

Be it known that I, DAVID S. KENNEDY, a citizen of the United States, residing at Brooklyn, in the county of Kings and State of New York, have invented certain new and useful Improvements in Typographical Machines, of which the following is a specification, reference being had therein to the accompanying drawing.

- 10 My invention relates to slug casting machines, such as linotype machines of the general organization represented in U. S. Letters Patent to O. Mergenthaler No. 436,532, wherein circulating matrices are released 15 from a magazine in the order in which their characters are to appear in print and then assembled in line, the composed line transferred to the face of the mold, the mold filled with molten metal to form a slug or 20 linotype against the matrices which produce the type characters thereon, and the matrices thereafter returned through a distributing mechanism to the magazine from which they started.
- 25 In these machines, the individual matrices are ordinarily provided with two characters, one roman and the other italic, and either of which may be brought into use as desired. In the use of characters of either kind, the 30 matrices are presented to the mold in a vertical position, and hence the italic characters must be and are inclined with relation to the parallel sides of the matrices. Under such 35 conditions, the italic characters on the cast slugs cannot of course overlap each other, i. e., intersect a line drawn vertically between them, as in the case of perfect italic characters.

40 My present invention is intended to obviate the foregoing disadvantage and contemplates certain improvements whereby slugs may be produced with the regular roman characters or with perfect italic characters, as desired. The exact manner in 45 which this result is accomplished will be best understood from the detailed description to follow.

45 In the accompanying drawings, I have shown my invention merely in preferred 50 form and by way of example, and as applied to a linotype machine of the general class stated, but obviously there are various other embodiments and adaptations which will still be comprised within its spirit. Thus, 55 for instance, it is applicable to all forms

of typographical machines, whether the product thereof be linotypes, logotypes, or single types or dies. Generally speaking, I desire it to be understood that I do not limit myself to any specific form or embodiment, 60 except in so far as such limitations are specified in the claims.

Referring to the drawings:

Fig. 1 is a front view of a portion of a linotype machine having my invention embodied therein;

Fig. 2 is a vertical section taken through the casting devices and showing the parts in condition for casting a slug with roman characters;

Fig. 3 is a front view of the line clamping and justifying devices, illustrating the action of these parts in connection with a composed line of inclined matrices;

Fig. 4 is a view similar to Fig. 2 but showing the parts in condition for casting a slug with italic characters;

Fig. 5 is a perspective view of an improved matrix; and

Fig. 6 is an edge view of the matrix as it appears in its different operative positions.

Referring to Fig. 1, the matrices X and the spacers Y are delivered one by one to the assembler A, wherein they are composed in line in the usual way (see the dotted lines). After composition, the assembler is lifted and the composed line transferred through the intermediate channel B to the dotted line position D, when it is received by the first elevator C, which thereupon descends and presents it between the clamping jaws F and G. The mold E (Figs. 2 and 4) is then advanced by its carrying disk E¹ into close contact with the composed line at the front, and the pot mouth E² is similarly advanced into close contact with the mold at the rear, after which the molten metal is injected in the usual manner. Prior to the casting operation, the composed line is both aligned and justified, the aligning action being effected by a slight upward movement of the first elevator, and the justifying action being effected by the upward movement of the justifying slide K which serves to force the spacers Y through the line and to extend it between the jaws F and G. After casting, the composed line is carried upward by the first elevator to the dotted line position D², where the matrices and spacers are shifted to the upper transfer

channel and second elevator for return to their original places of storage. The foregoing parts are or may be the same as embodied in the commercial linotype machines, 5 except in so far as hereinafter pointed out.

The present invention is directed to an improved construction of the parts whereby the matrices of a composed line may be presented to the mold either in a vertical position 10 for the casting of slugs with roman characters, or in an inclined position for the casting of slugs with italic characters. Referring first to the matrices, these are of the improved form illustrated in Figs. 5 and 15 6. As there shown the matrix is formed in one edge with two superposed intaglio characters X^1 and X^2 , these characters being punched in the bottoms of routing notches X^3 . The roman character X^1 is 20 arranged on the matrix for alignment in a vertical position thereof, as shown at the left in Fig. 6, said character having its vertical axis extending parallel to the sides of the matrix; whereas the italic character X^2 is 25 arranged on the matrix for alignment in an inclined position thereof as shown at the right in Fig. 6, said character (unlike the ordinary italic character) having its vertical axis also extending parallel to the sides of 30 the matrix. In providing for such arrangement of the two characters, the customary projecting ears X^5 and X^6 of the matrix are formed on their inner ends with angularly related surfaces x^1 and x^2 , the surfaces 35 x^1 being disposed at right angles to the sides of the matrix so as to locate the latter in its proper vertical position when the roman character X^1 is used, and the surfaces x^2 being disposed at an inclination 40 to the sides of the matrix so as to locate the latter in its proper inclined position when the italic character X^2 is used. As viewed in another aspect, the surfaces x^1 and x^2 extend parallel to the base or datum lines of 45 the respective matrix characters X^1 and X^2 , as required to effect their proper alignment.

When it is desired to use the roman characters X^1 , the matrices X are handled in 50 practically the same way as in the commercial linotype machine, that is to say, they are composed in line in a vertical position and then maintained in that condition throughout their travel through the machine, 55 it being noted (see Fig. 1) that at this time the clamping jaws F and G are arranged with their matrix engaging faces in vertical position to correspond. It is also to be noted that, in this instance, the first elevator 60 C is allowed to descend to its lowermost level so as to bring the characters X^1 into registration with the mold slot. In the casting relation of the parts, as shown in Fig. 2, the surfaces x^1 of all the matrices stand 65 in horizontal alignment, the surfaces on the

upper ears X^5 resting upon the usual sustaining rails C^1 of the first elevator and the surfaces on the lower ears X^6 engaging the underface of the lower mold aligning lip e^1 , whereby the proper alignment of the 70 matrix characters is insured.

When it is desired to use the italic characters X^2 , the matrices are composed in line in a vertical position and transferred in that condition to the first elevator C , but 75 at this time the clamping jaws F and G are arranged with their matrix engaging faces in inclined position, so that as the line is carried down between said jaws, the matrices will be tilted or inclined in the required manner, see Fig. 3. In this instance, moreover, the first elevator C is arrested in a raised position by the customary two-letter device O so as to bring the characters X^2 into registration with the mold slot. 80 In the casting relation of the parts, as shown in Fig. 4, the surfaces x^2 of all the matrices stand in horizontal alignment due to the tilting of the matrices as before mentioned, the surfaces on the upper ears X^5 resting 85 upon the elevator rails C^1 , and the surfaces on the lower ears X^6 engaging the underface of the upper mold aligning lip e , whereby the proper alignment of the matrix characters is insured. It will be apparent 90 that when the matrices are thus inclined, the characters X^2 are caused to overlap each other and hence produce perfect italic characters on the cast slug.

In order to permit the adjustment of the 100 jaws F and G to the different positions as above referred to, they are constructed and arranged in the manner fully set forth in my co-pending application Serial No. 259-175, to which reference may be had if desired. Thus, as shown in Fig. 3, the jaw F is pivotally mounted at F^1 on the supporting plate H , being provided with a spring-pressed plunger F^2 which serves to hold it in either its vertical or inclined condition. 110 Similarly, the jaw G is pivotally mounted at G^1 on the supporting plate J , being provided with a spring pressed plunger G^3 to hold it in either its inclined or vertical condition.

The tilting of the matrices of the composed line necessarily involves a corresponding tilting of the wedge spacers Y . In order to prevent the breaking or bending of the spacers under such conditions, it is desirable to modify the action thereon of the 120 justifying slide K . Accordingly, the slide is provided with the relatively movable member L which is held in normal position by the compression spring L^1 acting against the projecting stud L^2 thereon. In ordinary operation, when the spacers are presented to the mold in vertical position the member L acts upon them in the usual manner; but when the spacers are inclined, as shown in Fig. 3, the member L is moved 125 130

laterally with relation to the slide K so that its justifying action will be in the direction of the inclination of the spacers. This lateral movement of the member L is effected by the piece M formed with a cam surface corresponding to the inclination of the spacers, so that as the justification slide rises, the member L is shifted laterally and the resultant effect is to force the spacers 10 through the line in the direction of their inclination. In the ordinary operation of the machine, the cam piece is shifted to the dotted line position indicated in Fig. 3 so as not to engage the member L as the justification slide rises. This feature is also disclosed in my pending application above referred to and hence requires no further discussion herein.

While I have herein shown my invention as applied to a two-letter matrix, it should be understood that it is equally applicable to matrices formed with a greater number of characters. Furthermore, in its broader aspects, my invention does not require the use of a roman character in connection with an italic character, as both characters might be italic, in which event the matrices would merely need to be presented to the mold in different inclined positions as distinguished from the vertical and inclined positions herein discussed. In other words, my invention comprehends a matrix formed with a plurality of characters arranged thereon for alignment in different angular positions thereof, whether one of such positions be vertical and the other inclined or whether both be inclined. Again, it is not essential that both characters be arranged on the same edge of the matrix, as they could 40 very readily be placed on opposite edges, if that were desired or preferred. As previously stated, I have shown my invention merely in preferred form and by way of example, and obviously many changes and alterations therein will suggest themselves to those skilled in the art without departure from its scope.

Having thus described my invention, what I claim is as follows:

50 1. In or for a typographical machine, a matrix formed with a plurality of characters arranged thereon for alignment in different angular positions of said matrix.

2. In or for a typographical machine, a 55 matrix formed with a roman character and an italic character, the former being arranged on the matrix for alignment in a vertical position thereof, and the latter being arranged on the matrix for alignment in an inclined position thereof.

60 3. In or for a typographical machine, a matrix formed with a plurality of characters arranged thereon for alignment in different angular positions of the matrix, said 65 matrix being formed further with means to

locate it in one position or another according to the character in use.

4. In or for a typographical machine, a matrix formed with a roman character and an italic character, the former being arranged on the matrix for alignment in a vertical position thereof, and the latter being arranged on the matrix for alignment in an inclined position thereof, said matrix being formed further with means to locate it 70 in one position or the other according to the character in use.

5. In or for a typographical machine, a matrix formed with a plurality of characters arranged thereon for alignment in different angular positions of the matrix, said matrix being formed further with angularly related surfaces arranged to locate it in one position or another according to the character in use.

6. In or for a typographical machine, a matrix formed with a plurality of characters arranged thereon for alignment in different angular positions of the matrix, said matrix being provided with projecting ears, each formed at one end with angularly related surfaces arranged to locate the matrix in one position or another according to the character in use.

7. In or for a typographical machine, a matrix formed with a plurality of characters arranged thereon for alignment in different angular positions of the matrix, said matrix being provided at its upper end with a pair of supporting ears and at 100 its lower end with a mold contacting ear, said ears being formed on their inner ends with angularly related surfaces arranged to locate the matrix in one position or another according to the character in use. 105

8. In or for a typographical machine, a matrix formed with a roman character and an italic character, the former being arranged on the matrix for alignment in a vertical position thereof, and the latter being arranged on the matrix for alignment in an inclined position thereof, said matrix being provided at its upper end with a pair of supporting ears and at its lower end with a mold contacting ear, said ears 115 being formed on their inner ends with angularly related surfaces arranged to locate the matrix in one position or the other according to the character in use.

9. In a typographical machine, the combination of a composed line of matrices, each formed with a plurality of characters arranged thereon for alignment in different angular positions of said matrix, means for supporting the composed line with the matrices in one angular position or another according to the characters selected, and means for producing a slug from the composed line. 120 125

65 10. In a slug casting machine equipped 130

- with matrices, each formed with a plurality of characters arranged thereon for alignment in different angular positions of said matrix, the combination of means for composing the matrices in line, a mold, and means for presenting the composed line in casting relation to the mold with the matrices in one angular position or another according to the characters selected.
- 10 11. In a slug casting machine equipped with matrices, each formed with a roman character arranged thereon for alignment in a vertical position thereof, and with an italic character arranged thereon for alignment in an inclined position thereof, the combination of means for composing said matrices in line, a mold, and means for presenting the composed line in casting

relation to the mold with the matrices in either a vertical or an inclined position, according to the characters selected. 2

12. In a slug casting machine equipped with matrices, each formed on one edge with a plurality of superposed characters arranged thereon for alignment in different angular positions of the matrix, the combination of means for composing said matrices in line, a mold, and means for presenting the composed line at different levels with reference to the mold and with the matrices in one angular position or another according to the characters selected. 20

In testimony whereof, I have affixed my signature hereto.

DAVID S. KENNEDY.
